UNITED STATES PATENT OFFICE.

JOSEPH FAWELL, OF PITTSBURG, PENNSYLVANIA.

BLOWING-ENGINE.

No. 834,512.

Specification of Letters Patent.

Patented Oct. 30, 1906.

Application filed March 18, 1903. Serial No. 148,372.

To all whom it may concern:

Be it known that I, JOSEPH FAWELL, a citizen of the United States, residing at Pittsburgh, in the county of Allegheny and State of Pennsylvania, have invented or discovered certain new and useful Improvements in Blowing-Engines, of which improvements the following is a specification.

The invention described herein relates to 10 certain improvements in blowing-engines, and has for its object a construction whereby pressure is prevented from accumulating in the blowing-cylinder by leakage through the outlet-port thereof, and a consequent shifting 15 of the pistons of the blowing-cylinder and the steam-cylinder.

The invention is hereinafter more fully described and claimed.

In the accompanying drawings, forming a 20 part of this specification, Figure 1 illustrates diagrammatically a pair of blowing-cylinders and operating-engines with connections from the ends of the blowing-cylinders to a central point. Fig. 2 is a sectional view of a portion of 25 a blowing-cylinder, showing relief-valve device connected by a tube. Fig. 3 is a top plan view of a portion of the blowing-engine. Fig. 4 is a sectional plan view on a plane indicated by the line IV IV, Fig. 3; and Fig. 5 is a 30 view, partly in plan and partly in section, of the blowing-cylinder and its connections on an enlarged scale.

In the practice of my invention the blowing-cylinder 1 and its piston 2 and the valves 35 3 and 4, controlling the in and out flow of air to and from the cylinder, are constructed in the usual or any suitable manner. A suitable form or construction of valve mechanism for controlling the inflow of air consists 40 of a grid 4, movably mounted upon a seat 5, having radial slots or ports 5^a therethrough communicating with the interior of the blowing-cylinder. This grid is adapted to be shifted on its seat to open and close the ports 45 5^a by suitable actuating mechanism operated from the power-shaft of the engine and connected to the grid by the rod 6. A spring-seated valve 3, of any usual or suitable form of construction, is employed for controlling 50 the outflow of air from the cylinder into a chamber formed in the head or other suitable reservoir containing air under pressure, a suitable form of construction of outlet-valve mechanism being shown and described in 55 Letters Patent No. 632,490, granted September 15, 1899, to J. Hemphill. It sometimes

happens that a piece of dirt or other foreign material will prevent the outflow-valve 3 from firmly closing on its seat, and hence when the engine is at rest there will be a leakage, and consequent accumulation of air under pressure at the end of the cylinder having the inlet-valve closed. This pressure accumulates sufficiently to force the piston backward and through it effecting a corresponding movement of the piston of the steam-engine. In order to prevent such an accumulation of air under pressure, escape-ports 7 are provided leading from the ends of the cylinder and provided with a valve mechanism 60 normally held in closed position, so as to prevent any leakage from the cylinder through such port during the operation of the engine. Such a valve mechanism is arranged at each end of the blowing-cylinder and suitable connections are employed extending from such valve mechanism to a convenient point—as, for example, the throttle-valve of the steam-engine—so that when the blowing-engines have been stopped these connections can be 65 operated so as to open the valves and allow escape of pressure from the ends of the cylinders. A convenient construction of valve mechanism is shown in Fig. 2, and consists of a case or shell 8, having an outlet-port 9, arranged on one side of a diaphragm 8^a, through which is formed an opening adapted to be closed by a valve 10. This valve 10 is provided with a piston 11, fitting within the shell, the outer end of which has a valved 70 connection with the pressure-reservoir 12, connected to the blowing-engine or to other suitable source of fluid under pressure. During the operation of the blowing-engine this valve connection is opened, so that the valve 75 10 will be held to its seat by a fluid-pressure equal or approximately equal to pressure within the blowing-cylinder. While the valve 10 might be opened by pressure accumulating in the blowing-cylinder, it is preferred to effect such opening movement by 80 springs 13.

For convenience of operation the cases or shells of release-valve mechanism 8 are connected by pipes 14, leading to a valve mechanism 15, located at a convenient point—as, for example, a point near the throttle-valve of the steam-engine. This valve mechanism 15 is also connected by a pipe 16 to a reservoir containing air under pressure. As soon 85 as the engineer closes the throttle-valve of the engine he releases by a shifting of the valve 90

15 the fluid-pressure in these pipes 14 and release-valve mechanisms 8, permitting the leakage-controlling valves 10 to open and permit the escape of any fluid under pressure 5 which may flow into the blowing-cylinders. When the blowing-engines are to be started, the valve mechanism 15 is shifted, so that pressure will flow into the cases or shells 8 and close the valves 10.

10 I claim herein as my invention—

1. The combination of the cylinders of a blowing-engine, provided with leakage-ports, leakage-valves connected to said ports and adapted to be closed by fluid-pressure generated by the operation of the blowing-engine, and a valved connection controlling the flow 15

of fluid-pressure to said valves, substantially as set forth.

2. The combination of a cylinder of a blowing-engine provided with ports at or near its ends, leakage-valves connected to said ports and adapted to be closed by fluid-pressure generated by the operation of the engine, springs for opening said valves, and a valved connection from said valves to the source of 20 fluid-pressure, substantially as set forth.

In testimony whereof I have hereunto set my hand.

JOSEPH FAWELL.
